CHARLES SURMANN AND ROBERT D. DOUGLAS, OF FALL RIVER,
MASSACHUSETTS.

TUBE OR ROLL FORMING MACHINE.

SPECIFICATION forming part of Letters Patent No. 749,114, dated January 5, 1904.

Application filed January 16, 1903. Serial No. 139,307. (No model.)

To all whom it may concern:

Be it known that we, CHARLES SURMANN and ROBERT D. DOUGLAS, citizens of the United States, and residents of Fall River, in the 5 county of Bristol and State of Massachusetts, have invented new and useful Improvements in Tube and Roll Forming Machines, of which the following is a full, clear, and exact description.

10 This invention has relation to certain novel and useful improvements in a machine for forming tubes, rolls, or the like, and has particular application to a mechanism of this character adapted to wind tubes, cloth, or the 15 like.

Primarily we have in view as an object the production of a tubing-machine the sections whereof forming the mandrel will be capable of being readily moved toward or from each 20 other, thus enabling the tube or roll to at all times have a positive bearing or support inside the same, yet when it is desired to remove the tube or roll from the mandrel the circumference of the latter may be decreased, 25 whereby the roll or tube may be easily and readily slipped from the same.

A further object of the invention is the utilization of an improved means which may be readily moved into and out of position between the free longitudinal edges of two pivoted sections, which sections form the mandrel, such means being adapted, when in conjunction with the sections, to form a relatively enlarged mandrel having a smooth circumferential surface.

We also contemplate providing an improved construction for moving the mandrel-expanding means into and out of position between the free edges of the sections, whereby 40 we are enabled to avoid the use of cumbersome and complicated toggle-joints, sliding rods, and the like.

A further object of the invention is to provide means for drawing the free edges of the 45 sections into contact, thereby reducing the circumference of the mandrel when the expanding means have been moved from between the edges.

With these and other objects of a similar 50 nature in view our invention consists in the construction, combination, and arrangement

of parts, as described in this specification, delineated in the accompanying drawings, and set forth in the appended claims.

Reference is to be had to the accompanying 55 drawings, forming a part of this specification, in which similar characters of reference indicate corresponding parts in all the figures.

Figure 1 is a central longitudinal sectional view of our improved mandrel having a tube 60 thereon, the frame and other interior portions being shown in full lines. Fig. 2 is a transverse vertical sectional view of a mechanism embodying our improvements, the sections of the mandrel being shown in their enlarged 65 or expanded position. Fig. 3 is a similar view, but showing the mandrel in its contracted position. Fig. 4 is a view of one of the supports or standards forming a part of the interior frame of the mandrel. Fig. 5 is 70 a detail perspective view showing the key employed in operating the mandrel-expanding means, and Fig. 6 is a detail perspective view of a fragment of the key-bar.

In the accompanying drawings, wherein 75 there is delineated a mechanism embodying our improvements, 1 designates a shaft or axle which is rotatably mounted in any preferred manner and which may be driven or actuated by any suitably-applied power. 80 Upon this shaft we have mounted standards or supports which form what for the sake of convenience we term the "main frame." As will be seen especially by reference to Figs. 1 and 4, these supports comprise collar-like 85 portions 2 2, each having an enlarged member or standard 3 formed at one end thereof, a bore extending entirely through the collars, and the enlarged member for the passage of the shaft 1. The members of the frame may 90 be secured rigidly to the shaft in any approved manner, such as by bolts or pins, which pass through the collar portions 2 2 and through the shaft, such pins being shown in dotted lines in Fig. 1. Each of the members or portions 3 3 is provided with an extension or ear 4, which is apertured or bored, as at 5, (see Fig. 4,) to permit the passage of the rod 6, the construction being such that the apertured portions of these supports or standards 100 form bearings for said rod. The rod 6 is provided with a collar or washer 7 near each end,

which collars bear against the outer surfaces of the extension 4, and bearing against these washers or collars 7 7 are apertured lugs 8, formed on the interior edge surfaces of the 5 approximately semicylindrical mandrel-sections 9. As will be observed particularly by reference to Fig. 2, the under surfaces of the free longitudinal edges of the sections are beveled or inclined, as at 10, for a purpose to 10 be hereinafter described, the immediate contiguous portions of the sections being approximately flat or parallel to each other, as at 11. It is to be noted that when the sections are closed so that the edges 11 are in a 15 position to contact the mandrel has its smallest possible diameter in cross section. For the purpose of expanding the mandrel we have provided the following means: Formed in the end of each of the supports 3 3, oppo- 20 site the ear 4, is an orifice 12, each orifice being adapted to permit the passage therethrough of an end portion of a bar 13, approximately similar in construction and proportions to the rod 6. Each end of said bar 25 is formed with a flattened or squared portion 14 to provide a grasping or gripping surface for a wrench, and mounted near each of the flattened portions is a cam-key comprising a collar portion 15, adapted to be secured 30 through the medium of a suitable screw 16 to the bar 13, and formed integral with this collar portion is an extension or cam 17. Each of the supports 3 3 is provided with a socket or radially-extending bore 18, as is shown by 35 dotted lines in Fig. 1, and within each socket is adapted to be seated a stud 19, the stud being connected with and supporting a key-bar 20. This key-bar forms an important feature of the invention and has its upper surface 40 slightly convexed, as at 21, and inclined downwardly and outwardly away from the curved surface are the sides or shoulders 22, a short vertical abutting wall 23 being formed between the convexed top and the upper edge of 45 the shoulder, such wall being adapted when the bar is in its mandrel-expanding position to bear against the vertical edges 11 of the sections of the mandrel 9. Secured a short distance from each end of the bar and extending 50 downwardly from the under surface thereof is a plate 24, provided with a slotted or recessed portion 25, adapted to form a lip or extension 26, the recess being in alinement with the curved extension or cam portion 17 of the key, 55 the construction being such that when the shaft or bar 13 is turned for the purpose of moving the bar radially outward the cams 17 of the keys 15 will strike against the upper walls 27 of the plates 24 and move the bar; 60 but when it is desired to draw the bar radially inward the key is turned in the opposite direction and the cam portion abutting against the lower shoulder or lip 26 forces the key inward. For the purpose of drawing the semi- 65 cylindrical sections into a position of contact any suitable means may be employed, such as the tension-springs 28, connected at one

end to the shaft 1 through the medium of hooks 29, and at the outer ends these springs are secured to the semicylindrical sections of the mandrel 9 by similar hooks 30. It is of course to be understood that any suitable number of these springs may be employed and any suitable number of keys and plates, this depending upon the size of the machine. 75 The outward movement of the cam-key away from the locking-bar is limited by stops or studs 31, formed on the frame-standards 3.

From the above description, taken in connection with the drawings, the construction 80 and operation of the machine will be readily apparent. The key being forced radially outward spreads the sections or jaws of the mandrel into the position shown in Fig. 2 and the strip of paper or the material A to 85 be rolled is wound around the mandrel to the desired thickness. When it is desired to remove the tube from the mandrel, a wrench or other suitable means is applied to the flattened or squared end of the rod 13 and such 90 rod is turned to bring the cam portion of the key into contact with the lower shoulder and the key-bar is turned radially inward toward the main shaft. The tension-springs as soon as the key-bar leaves the space between the 95 semicylindrical mandrel-sections draw the latter together into abutment or contact at their longitudinal edges, and the circumference of the mandrel being thereby greatly reduced the tube or roll may be slipped from 100 the same.

Many advantages incident to a device of this character will be immediately apparent. It is to be noted that we avoid the use of toggle-rods, levers, and the like for holding the mandrel in its expanded or reduced position and at the same time have provided a structure which is economic, extremely durable, and capable of acting with great positiveness. Heretofore in devices of this general character one disadvantage has been incident to the same—namely, that when an attempt was made to remove a tube or roll from the mandrel only a small section of the semicylindrical wall could be moved inward, the main 115 portion of the circumference being fixed or rigid, and it was necessary to strike the tube a sharp blow upon the body or circumference thereof to loosen the same upon the mandrel, which striking or tapping oftentimes resulted 120 in the abrasion or damaging of the material and the flattening or distortion of the tube. In the present instance the diameter of the mandrel-body is so reduced that the tube may be removed with facility and without 125 any such striking or tapping as has been mentioned. It is to be observed that in addition to forming paper tubes or the like upon our mandrel it is also exceedingly convenient for the purpose of winding cloth or any material, in fact, this being accomplished by placing a paper tube upon the mandrel and expanding the latter, so that it frictionally holds the tube, and then winding the 130

cloth or other products upon the said tube. When the desired quantity of goods has been rolled or wound upon the tubes, the size of the mandrel is reduced, as heretofore explained, and the tube with the goods thereon is removed.

While we have shown and herein described one particular embodiment of our invention, we wish it to be understood that we do not limit ourselves to the precise details of the illustration herein, as there may be modifications and variations in some respects without departing from the spirit of the invention or sacrificing any of the advantages thereof.

Having thus described our invention, we claim as new and desire to secure by Letters Patent—

1. A tubing-machine comprising frame members spaced apart, a rod passing through and connecting said members, sections forming a mandrel pivoted to said rod, means adapted to pass between the sections for expanding the same, and means independent of the expanding means for contracting said mandrel, substantially as set forth.

2. A tubing-machine comprising a driven shaft, frame members formed with collars, and screws passing through said collars so that the frame members are mounted to turn with said shaft, a rod passing through and connecting the frame members, sections forming a mandrel pivoted to said rod, and means movable into alignment with the free edges of the sections, whereby to expand the mandrel and preserve a smooth continuous surface, substantially as set forth.

3. A tubing-machine comprising a revolute shaft, frame members mounted to turn with said shaft, a rod supported by and connecting the frame members, sections forming a mandrel hinged to the frame-connecting means, means for expanding the mandrel, means for moving the expanding means into and out from a position between the free edges of the sections, and means for drawing the sections toward each other when the expanding means are moved from between the edges of the same, substantially as set forth.

4. A tubing-machine comprising hinged sections forming a mandrel, expanding means for the same, a recessed projection on the expanding means, a key for engaging the recessed projection to move the expanding means into and out of position between the edges of the sections, and a stop for limiting the movement of the key away from the expanding means, substantially as set forth.

5. A tubing-machine, comprising hinged sections forming a mandrel, means for expanding the mandrel, rotatably-mounted means for moving the expanding means radially into and out from a position between the free edges of the sections, and spring-tension means connected with the mandrel-sections for automatically drawing the sections toward each other when the expanding means are

moved from between the edges of the sections, substantially as set forth.

6. The combination of a frame, sections forming a mandrel hinged to the frame, a bar, studs on said bar fitting into sockets formed in the frame, the construction being such that the bar may be moved into a position between the longitudinal free edges of the sections, and contraction-springs for drawing the mandrel-sections inward.

7. The combination of a frame, sections forming a mandrel hinged thereto, a bar radially movable relative to the frame, means including a key-head for moving said bar into and out of position between the free edges of the sections, and tension devices for drawing the sections toward each other when the bar is moved from between the edges of the same.

8. The combination of a frame, sections movably connected thereto, a radially-movable bar, a longitudinally-arranged rod revolvably mounted in the frame and a key-head on said rod adapted to engage with the bar for moving the latter into and from a position between the edges of the sections.

9. The combination with a driven shaft, and supports rigid thereon, said supports forming a frame, of a rod secured in said frame, hollow semicylindrical sections forming a mandrel pivoted at adjacent edges to said rod, whereby the sections may be moved outward relative to each other, a bar having a convex upper surface adapted to be moved into and out of position between the free edges of the sections and means including a rotatable key-shaft and a key-head secured thereto for moving said concaved bar, and springs for drawing the free edges of the sections into a position of contact when the bar is moved from between said edges.

10. The combination with a frame, sections forming a mandrel hinged thereto, means including a bar, and a rotatable shaft having a key-head adapted to engage with said bar, for moving the sections outward relative to each other, and springs for drawing the sections inward.

11. The combination of a revolute shaft, supports forming a frame mounted on said shaft, a rod extending through said frame, approximately semicylindrical sections pivotally secured to said rod, a bar having a convex upper surface supported in the frame and movable radially outward to a position between the free edges of the sections, whereby to enlarge the circumference of the mandrel and at the same time preserving a continuous surface and enabling a tube to be formed thereon, and means for drawing the free edges of the sections into contact when the bar is removed from between the same, whereby to enable the tube to be easily removed from the mandrel, substantially as set forth.

12. The combination with a revolute shaft and supports forming a frame, rigid thereon, of hollow, approximately semicylindrical sec-

tions pivoted to said frame at one edge, the upper under surface of the free edges of the sections being slightly beveled, a bar having a convexed upper surface and beveled shoulders adapted to be moved into a position between the aforesaid free edges, the construction being such that a continuous surface is formed between the bar and the sections, and means engaging with the bar for moving it into and out of such position between the edges.

13. The combination with a revoluble shaft and supports forming a frame, rigid thereon, of hollow, approximately semicylindrical sections pivoted to said frame at one edge, the lower surface of the upper free ends of the sections being slightly beveled, a bar having a convexed upper surface and beveled shoulders adapted to be moved into a position between the aforesaid free edges, the construction being such that a continuous surface is formed between the bar and the sections, a recessed plate secured to said bar, and a key

revolubly mounted in the frame and adapted to seat in the recessed portion of the plate for moving the bar into and out of position 25 between the edges of the sections.

14. The combination of a revoluble shaft, a frame mounted on said shaft, such frame having a socket formed therein, sections forming a mandrel secured to said frame, and means supported in the socket portion of the frame, and movable between the mandrel-sections for moving such sections outward relative to each other, substantially as set forth.

35 In testimony whereof we have signed our names to this specification in the presence of two subscribing witnesses.
